J. W. NEAL AND A. J. TRUXELL, OF BIG LICK, VIRGINIA.

Letters Patent No. 83,198, dated October 20, 1868; antedated October 9, 1868.

IMPROVEMENT IN COCKLE AND GARLIC-SEPARATOR

The Schedule referred to in these Letters Patent and making part of the same.

To all whom it may concern:

Be it known that we, J. W. NEAL and A. J. TRUXELL, of Big Lick, in the county of Roanoke, and in the State of Virginia, have invented certain new and useful Improvements in Cockle and Garlic-Separator; and do hereby declare that the following is a full, clear, and exact description thereof, reference being had to the accompanying drawings, and the letters of reference marked thereon.

In the annexed drawings, making a part of this specification—

A represents a frame, of any suitable form and size, and made of any desired material, and B B represent cylinders or rollers, adjusted or secured, and working in said frame A.

The cylinders B B are adjusted at any angle desired, and are so arranged that the lower ends may be adjusted so as to give a greater or less inclination to said cylinders, to suit the kind of grain to be cleaned, and to correspond with the quantity of dirt or cockle and garlic in the grain. If a small amount of refuse substance be among the grain, a greater inclination should be given the cylinders.

These cylinders are provided with or have holes or recesses along their sides, as shown, into which the cockle and garlic will fall and be caught, while the grain will slide down the inclination, and between the cylinders, and out at the spout D.

Attached to one end of one of the cylinders B is a crank, by which said cylinder is turned, and the other may be turned by the friction, or by any suitable device.

Any power may be applied to this machine, to drive it, that may be desired or most convenient. One cylinder, with an inclined platform, may be used, instead of two cylinders, and any number of pairs of cylinders may be used in or combined with this machine.

C represents a suitable hopper, which is provided with an arm, which hooks in the loops h on the frame, and is thereby secured in place. The mouth of the

hopper C is placed directly over or between the sides of the cylinders B B.

By pouring grain, mixed with cockle or garlic, or both, into the hopper C, and turning the cylinders B B by means of the crank or otherwise, the grain slides down the inclination, and out at the spout D, while the foreign matter is caught in the recesses x, and carried over and thrown out under said cylinders, in a trough or box for that purpose.

We do not claim broadly the arrangement of cylinders in an inclined manner, when provided with cells to retain the grain for the purpose of separating large and small grain, such as wheat from oats.

Our cylinders are covered with sheet-metal that is provided with perforations, as described, so as to allow the cockle to catch in the spaces, and the grain to pass down between the two cylinders, and out the spout at the end. These cylinders are arranged obliquely for the above purposes.

The above-described device is constructed as an improvement upon the cockle, garlic, and smut-separator, granted to the within-named J. W. NEAL, on the 16th day of July, 1867.

Having thus fully described our invention,

What we claim as new, and desire to secure by Letters Patent, is—

The arrangement of the cylinders B B, having perforated metal faces, upon the frame A, in such a manner that one end of each cylinder is elevated above the other, so that the grain will pass from the hopper C down in between the cylinders, and pass down the inclined plane thus formed, all constructed and used as specified.

In testimony that we claim the foregoing, we have hereunto set our hands, this 30th day of January, 1868.

J. W. NEAL.
A. J. TRUXELL.
